STOCK RECEPACLE

Matthew E. Hill, Atlanta, Ga., assignor to The
Holfast Rubber Company, Atlanta, Ga., a cor-
poration of Georgia

Application September 30, 1930
Serial No. 485,480

6 Claims. (Cl. 206—72)

This invention relates to stock receptacles such as drawer cabinets, shelves or the like for merchandising various articles, and particularly automobile fan belts which are commonly supplied in one or more types, such as V-shaped and flat, and in a large number of sizes.

My principal objects are to facilitate the storing and dispensing of these articles, and more particularly fan belts, by retail dealers and others, to enable the dealer to keep on hand a reasonably complete stock without overstocking, to rotate his stock by frequent replacements of the articles in each of the sizes so as to minimize the amount of deterioration due to aging of the articles in storage, and to enable him to maintain a running inventory of his merchandise without an expensive stock-listing and bookkeeping system.

There is little uniformity of practice among automobile manufacturers as to the dimensions of the fan belts used on the several cars and even the same make or model of car will sometimes require a different size belt in different years. Since the belts wear out and have to be renewed and it is often impossible for the car owner to find an agent for his particular make and model of car who can furnish the desired size and type of belt at the time and place required, retail merchandisers of automobile parts who can furnish practically all of the sizes of fan belts to fit the various cars are performing an important function in serving the requirements of the motoring public. By designing a line of replacement fan belts so that each size in the majority of cases can be used on a number of different models of cars, it is possible at the present time for the belt manufacturer to furnish practically a complete line with from 70 to 150 sizes, depending upon how close he wants to make the fit and how many unimportant sizes he omits. However, under the methods heretofore employed by the retailer in stocking these goods, which have involved storing the belts on hooks or more or less heterogeneously in bins, cabinet drawers or on shelves, without adequate provision for readily determining the various sizes required and on hand, it has been practically impossible for the dealer to avoid understocking or overstocking and to furnish his customers with a prompt and complete service of reasonably fresh goods. The tendency is to have on hand too many of the slower moving sizes in an effort to furnish complete service so that an unnecessarily large amount of capital is required to run this department of the business, customers are often furnished with goods which

have deteriorated from age and the service furnished is not as speedy as it might be.

My present invention, in a simple but very effective manner, furnishes a solution for these merchandising problems, and for the first time, so far as I am aware, provides the retailer with a merchandising device whereby he can furnish just as complete a fan belt service as he may desire, maintain an automatic inventory of goods practically without the necessity for listing or bookkeeping except when ordering replacements from the manufacturer, and with the smallest possible liability of accumulating an overstock of goods.

Of the accompanying drawing.

Fig. 1 is a front elevation showing one drawer and adjacent portions of a cabinet adapted to contain an embodiment of my invention.

Fig. 2 is a plan view showing the partially filled drawer and contents embodying my invention.

Fig. 3 is a vertical section on the line 3—3 of Fig. 2.

Fig. 4 is a plan view showing an example of the belt labels.

Referring to the drawing, 10 is a cabinet adapted to contain one or more sliding drawers or magazines for storing a collection of endless fan belts 12, 12 in accordance with the present invention, in this case narrow belts of V section which, as is customary, are held in the form of an elongated loop by a pasteboard wrapper or sleeve 13 into which the belt is slipped, or in some cases by a pasteboard carton. The interior of each drawer is accessible for vision and for inserting and removing the articles from the top.

A baseboard 14 is provided, extending lengthwise from front to rear of the drawer 11, substantially midway of the width of said drawer, and on this are mounted a series of separators 15 dividing the drawer space into a series of belt-holding compartments. Each of the separators 15 may conveniently be made of a stout piece of steel wire first bent into three-sided rectangular form, then passed through holes 16 in the board and then bent over horizontally inward at its ends 17 as indicated in Fig. 3, said ends occupying a groove 18 formed in the underside of the board 14 and being held against vertical movement between the top wall of said groove and the bottom wall 19 of the drawer.

The bottom 19 and side walls 20 of the drawer may conveniently be made of a single piece of sheet metal, such as galvanized iron, bent to shape

and nailed to the adjacent edges of wooden front and rear walls 21, 22, of which the latter may be somewhat lower than the former, while the metal side walls 20 may be lower than the front and rear walls. For securing the belt-holder baseboard 14 in place, I prefer to fasten its rear edge by nails 23 to the back drawer wall 22 and to place its front edge under the inner screw-fastening 24 by which the drawer pull-knob 25 10 is detachably secured to the front wall 21.

The board 14 and separators 15 constitute a multiple belt rack whose length or fore-and-aft dimension is substantially the same as that of the interior of the drawer, but whose width 15 is considerably less than the width of said interior, leaving free spaces on either side into which the belts project, so that one end of the looped belt can readily be grasped for the purpose of inserting it in or removing it from the 20 rack.

The belt maker customarily marks on the wrapper or the belt or both, a distinctive number or other indicium or designation for identifying each size of belt, the numbers having heretofore been placed on the sides of the wrappers or cartons, and furnishes his dealers with printed lists showing the various belt sizes for the several makes and models of cars and the corresponding factory number or designation for each 25 belt size. When the dealer is called upon to serve a customer with a belt, he first refers to the catalog furnished by his belt maker and ascertains the factory size number of the belt recommended. Then he goes to his stock for the 30 belt in question.

My invention involves numbering or otherwise individually designating the different belt sizes, but on the edge instead of the side of the wrapper or carton, and instead of relying solely upon such 40 marking in connection with the printed list or catalog, I also apply these same markings or indicia to the several belt-holding compartments in the drawer 11 or other storage receptacle. I further place these compartment markings in such a position that when a belt bearing a certain 45 number is in place, the compartment number identifying that belt will be concealed by the belt, and when the belt is removed from its compartment, that number will appear in a conspicuous location, such as the bottom of the compartment, and will show at a glance which 50 particular number has been sold and should be replaced when the stock is renewed. Thereby a quick and accurate inventory of stock is promoted because the identifying number pertaining to a particular belt appears to the salesman's vision 55 only once, either on the belt or at the bottom of its compartment, mistakes caused by diverting the eyes to find or compare locations are avoided, 60 and he can instantly determine the state of his stock and what replacements are required.

Thus in Fig. 2 the belts and their holder compartments are shown as consecutively marked with the numbers 361 to 368 (although some of a range of numbers may be omitted, as in illustration) and a label 26 is removably placed in a frame on the front of the drawer 11 to show that said drawer is devoted to that range of belt numbers as shown in Fig. 1. These numbers are placed on that edge of the belt which is to lie uppermost in the drawer, preferably on the sleeve or wrapper 13 enclosing the belt. The numbers designating the compartments are placed on labels 27 pasted on the upper face of 75

the baseboard 14 at the bottom of each belt compartment.

Conveniently the number may be placed on the belt wrapper by a printed label 28, which may also bear a designation of the size and type of the belt corresponding to that number as indicated in Fig. 4, and this may be overlapped with another label 29 pasted to the side of the wrapper and bearing a printed list of the makes and models of cars for which that size of belt is intended. In this way, the dealer and the customer will both have a check upon the correct selection of the particular belt desired.

These cabinets, with drawers having properly labeled belt-holding compartments and a corresponding stock of belts, are designed to be furnished by the belt manufacturer, whose experience teaches him the various sizes of belts required and the approximate relative demand which may be expected for the respective sizes in particular localities. Since certain sizes are more in demand than others, some of the numbers in the drawer 11 may be repeated, the illustration showing two each of the numbers 365 and 368 and one of each of the other numbers. 100 In this way the belt manufacturer, who has the necessary knowledge, can provide the dealer, who rarely possesses sufficient information to enable him properly to control his stock, with the minimum number of belts required to give 105 complete service to customers, without overstocking. The dealer has an automatic inventory at all times by merely referring to his cabinet, and he or the belt manufacturer's agent or jobber can easily and quickly replenish the stock as to 110 required belt numbers at convenient intervals.

From the foregoing it will be apparent that I have provided a greatly improved merchandising device for fan belts and other articles commonly furnished in a large variety of sizes. While I 115 have described a preferred embodiment, it will be understood that modifications may be made, features added or omitted and the details widely varied without departing from the scope of the invention as defined in the claims.

I claim:

1. A fan-belt merchandising unit comprising a receptacle accessible for vision from the top and including a plurality of compartments for holding the belts individually exposed to view from the top, each compartment having on its bottom an indicium identifying the belt which belongs there and so located as to be concealed by the belt when the latter is in place and exposed to view when said belt is removed, together with a series of fan belts each set edgewise in one of said compartments and each bearing on its top edge the same indicium as the compartment which it occupies.

2. A merchandising receptacle for articles such as fan belts, said receptacle being accessible for vision from the top and comprising a rack which includes a plurality of individual compartments for holding the articles edgewise in an upright position, each compartment having an indicium at the bottom thereof for identifying the article to be placed therein, said indicium being so located as to be concealed by the article when the latter is in place and exposed to view from the top when the article is removed.

3. A stock receptacle for articles such as fan belts, said receptacle comprising an outer container having therein a rack of less width than said container and including a plurality of separators defining individual compartments for hold-

ing the articles edgewise and upright, each compartment having an indicium at the bottom thereof to identify the article held therein, so located as to be concealed by the article when the latter is in place and exposed to view from the top when the article is removed.

4. A stock receptacle for articles such as fan belts, comprising a cabinet drawer having front and rear walls and a metal sheet forming the 10 bottom and side walls, a rack in said drawer composed of a base on the drawer bottom and wire separators of inverted U-shape having their ends fastened in the base, said separators defining individual compartments for holding the articles edgewise, each compartment having an indicium on the base for identifying the article which belongs in that compartment, so located 15 as to be concealed by the article when the latter

is in place and exposed to view from the top when the article is removed.

5. A fan-belt stock holder comprising a perforated baseboard transversely grooved underneath, a series of wire separators in the perforations defining belt compartments and having bent ends confined in the grooves, and additional means for retaining said ends in the grooves. 80

6. A stock drawer comprising front, rear and side walls, a metal plate forming the bottom wall, and an article holder in said drawer comprising a baseboard formed with transverse grooves in its lower face and metallic separators thereon each having its two lower ends confined in one of said grooves between and parallel with said baseboard and bottom plate. 85 90
